UNITED STATES PATENT OFFICE.

CHARLES A. EWING, OF STEELTON, PENNSYLVANIA.

HARDENING APPARATUS FOR RAILWAY AND TRAMWAY RAILS.

Application filed March 22, 1921. Serial No. 454,524.

To all whom it may concern:

Be it known that I, CHARLES A. EWING, a citizen of the United States of America, residing at Steelton, in the county of Dauphin 5 and State of Pennsylvania, have invented certain new and useful Improvements in Hardening Apparatus for Railway and Tramway Rails, of which the following is a specification.

10 This invention relates to certain new and useful improvements in hardening apparatus for railway and tramway rails, and for carbon steel in general and has particular reference to the hardening of steel to produce a hard and tough or sorbitic structure 15 of varying toughness throughout the steel.

In the usual hardening treatment of railway and tramway rails, wherein the rails are hardened by being subjected to a blast or

20 flow of elastic fluid such as air for producing a hard and tough or sorbitic structure in the head or ball of the rail, the rails are delivered from the rolling machines to a hot bed and thereafter manually shifted adjacent to an air supply device with the head of the rail positioned in proximity of the air supply.

25 With this process, the head, web and base flanges of the rail are entirely exposed with the result that the air supply not only contacts the head or ball of the rail but flows in contact with the rail webs and base flanges, the entire rail structure, with this process, being in effect subjected to the flow 30 of hardening medium whereby the rails are 35 improperly hardened i. e., the base flange of the rail being hardened in excess of the ball or tread.

The primary object of this invention resides in the provision of an apparatus operatively associated with the hot bed of a steel rail rolling mill to which hot bed the rails are successively delivered while heated to a temperature above the critical temperature with the present apparatus successively receiving the heated rails delivered to the hot bed and being automatic in its operation for continuously hardening the rails until their point of discharge from the apparatus.

A further object of the invention has reference to a machine associated with the hot bed of a steel rail rolling mill with cooperating devices forming elements of said apparatus and hot bed for successively moving the rails delivered to the hot bed to the apparatus for purposes of hardening the same.

A still further object of the invention embodies a novel form of apparatus for successively receiving rails delivered to the hot bed of a rolling mill and moving the rails to a position on said apparatus whereby the 60 heads or balls alone of the rails are subjected to the hardening medium during their association with said apparatus.

The invention further contemplates improvements in the manner of positioning the 65 rails to be hardened on the supporting medium, said medium preferably consisting of a rotatable drum and having adjustable flanged plates or bars engaging the sides of the rail heads or balls to prevent the escape 70 of the hardening medium such as air for contact with the rail webs and base flanges and confining the same for contact with the head or balls alone of the rails.

The invention further contemplates, as an 75 advance in the art, novel types of rail engaging clamps associated with the hardening apparatus herein disclosed, whereby rails of various sizes are capable of treatment in a machine or apparatus of standard construction.

The invention further embodies in an apparatus of the type hereinafter described a plurality of clamping levers for holding the rails in fixed position on the apparatus during the hardening process with a novel form of cam operating device for said clamping levers, said cam device being adjustable relative to said apparatus whereby the points of reception and discharge of the rails on the 80 apparatus may be changed, to accommodate the apparatus for association with hot beds and discharge chutes of different heights.

The invention further provides for a novel 85 type of rail head supporting members carried by the tempering apparatus, said supporting members being pivotally mounted on the apparatus and moved to an open position when freeing a rail and adapted to be moved to a closed position to confine the 90 head of the rail when a rail is positioned therein by the rail supporting clamp.

With the above general objects in view and others that will become apparent as the 95 nature of the invention is better understood, the same consists of the novel form, combination and arrangement of parts hereinafter more fully described, shown in the accompanying drawings and claimed.

In the drawings, wherein like reference 110

characters designate corresponding parts throughout the several views,

Figure 1 is a longitudinal sectional view of a rail tempering machine constructed in accordance with the present invention, there being illustrated a rotatable drum for supporting the rails and an air supply pipe within the drum.

Figure 2 is a cross sectional view of the tempering apparatus showing the valves for controlling the supply of hardening medium to the rail heads and the automatically operating feed devices for successively delivering the rails from the hot bed to the hardening apparatus.

Figure 2^a is a cross sectional view taken on line II^a—II^a of Fig. 1 showing the positive cam for operating the rail supporting clamps,

Figure 3 is a detail sectional view of a modified form of the invention showing the rack bar operated rail head engaging plates for directing the hardening medium onto the rail heads and the laterally adjustable rail engaging clamp,

Figure 4 is a detail sectional view of another form of the invention showing the pivotally mounted rail head engaging members and the rail clamp attachments for steadily the base flanges of the rails,

Figure 5 is a cross sectional view taken on line V—V of Fig. 1 showing the adjustable positively operating cam for shifting the rail engaging clamps,

Figure 6 is a detail sectional view taken on line VI—VI of Fig. 3 showing the side opening vents for the rail receiving pockets, the operating shaft for the rail engaging clamps and the pinion and supporting shaft for laterally shifting the rail head engaging plate, and

Figure 7 is a fragmentary detail sectional view of a modified form of the invention showing the rail heads supported upon transverse partitions in the rail head receiving pockets of the drum.

This invention is continuous in operation, i. e., the rails being delivered from the rolling mills are received on a hot bed and while the heat of the rails is above the critical temperature, the rails are successively fed along the hot bed to a rotating drum that successively receives the rails and hardens the heads of the rails while supported thereon and delivers the rails for discharge from the drum to a receiving trough or platform. The rotating drum is adapted to be driven at various speeds to effect the proper tempering of the rails as for instance, rails of 50 carbon steel will require a longer period of time for hardening than rails of 75 carbon steel. The rotating drum supporting the rails is operated in any suitable manner and the rotating drum cooperates with the feeding means of the

hot bed in timed relation for receiving the rails as the same are fed along the hot bed. The drum supporting the rails is provided with an axial supply pipe for the hardening medium having lateral ports therein for delivering the hardening medium to the interior of the drum, and the periphery of the drum is provided with longitudinal pockets into which the rail heads to be hardened are received, clamp levers being carried by the periphery of the drum and operated by a cam device for holding the rails in the pockets and permitting the discharge of the rails from the drum, a plurality of valves having relatively long stems controlling the passage of the hardening medium from the interior of the drum to the pockets, the valve stems extending a material distance into pockets to be engaged by the heads of the rails when clamped home to open the valves and permit the flow of hardening medium in the drum through the valve openings for contact with the rail heads, devices being associated with the rail to confine the flow of hardening medium onto the rail heads and to prevent the hardening medium from contacting the rail webs and base flanges, said valves being automatically closed when the cam operated clamping levers move to a position to discharge the rails from the drum. The rails in being delivered from the rolling mills are sawed into the desired lengths, and passed through cambering rollers to slightly distort or camber the same, with the head of the rail lying in the inner arc and to accommodate the cambered rails to the drum so that the heads thereof at the inner arc of the camber will be wholly received within the pockets of the drum, said drum is preferably formed of a substantially oval shape with the greatest bilge intermediate the ends thereof.

This application is a continuation in part so far as illustrated, described and claimed in my application for method of and apparatus for treating steels filed December 23, 1920, Serial No. 432,759 and embodies improved devices for carrying into operation the method as expressed in my prior application and further set forth herein.

The invention as disclosed in the accompanying drawings shows preferred forms of apparatus and it is not intended that the invention be so limited, there being illustrated end standards 1 and 2 connected by a base plate 3 for supporting a rotary drum. The drum embodies end walls 4 and 5 connected by an oval wall 6, the drum being rotatably supported in the end standards 1 and 2.

The rotatable support for the drum includes a stub shaft 7 journaled in the standard 2 and forming an integral part of the end wall 5 of the drum, a cup bearing 8 ex-

tending inwardly of the end wall 5 for purposes presently to appear. A supply pipe 9 for the hardening medium has one end thereof fixed to the upper end of the standard 1 by the strap bearing 10, the pipe 9 extending axially of the drum 6 with the inner end thereof journaled in the cup bearing 8 as illustrated in Fig. 1. An annular bearing flange 11 is formed axially of the end wall 10 4 of the drum and is rotatably supported on the pipe 9, the flange 11 having anti-friction bearing balls 12 positioned between said flange and the pipe 9 while a packing 13 engaged by the gland 14 seals the interior 15 of the drum 6 to the atmosphere. Lateral ports 15 are provided in the pipe 9 to permit the flow of hardening medium from the pipe to the exterior of the drum. To effect rotation of the drum in the bearings 1 and 2, 20 the drive shaft 16 journaled in the standard 2 carries a pinion 17 meshing with the gear 18 fixed to the stub shaft 7, the gear 18 being in mesh with the gear 19 carried by the shaft 20 in the standard 2 for rotating said gear 25 19 for purposes presently to appear.

To accommodate the mounting of rails on the periphery of the drum 6, said drum is provided with a plurality of spaced longitudinally extending pockets 21 having transverse partitions 22 provided with ports 22' with longitudinally spaced valve seats 23 formed in the inner wall of the pockets 21 as clearly shown in Figs. 1 and 2. A plurality of annular bands 24 are supported 30 within the drum 6 in spaced relation by the brackets 25 fixed to the inner wall of the drum with a band alined with the valve seats 23 in circular series, while a valve 26 has an inwardly extending stem 27 slidable 35 through the band 24 and an outwardly extending elongated stem 28 extending through the pocket partition 22, springs 29 surrounding the valve stems 27 between the valve 26 and band 24 normally to hold the valves 26 40 in closed position on their seats 23. It will therefore be seen that hardening medium of elastic fluid such as air entering the open end of the pipe 9 is confined within the drum 6 by the valves described. In the form of 45 the invention as shown in Figs. 1 and 2 resiliently mounted plates 30 are supported at the outer ends of the side walls of the pockets 21 and have right-angularly extending inwardly directed flanges 31 projecting 50 into the open pockets 21 with the flanges 31 in each pocket being normally spaced as illustrated. The plates 30 are provided with transverse slotted openings through which retaining pins 32 project to permit limited 55 sliding movements of the plates on the periphery of the drum 6, stems 33 being carried by the outer faces of the plate flanges 31 and slidably extending through the side walls of the pocket openings as shown in 60 Fig. 2 and surrounded by coil springs 34

normally tending to move the plate flanges toward each other for the resilient gripping of the opposite sides of a rail head.

A plurality of rail engaging clamps is associated with each pocket 21, each clamp including a lever 35 pivotally mounted upon the bracket 36 with the levers and brackets of each pocket longitudinally alined while the outer end of the clamping lever 35 is fashioned as at 37 for engaging the base 75 flange and web of a rail for delivering the same to a pocket for hardening treatment.

The operating means for the clamping levers 35 embodies provision of peripherally spaced longitudinally extending channels 80

38 formed in the drum, one associated with each pocket 21 and having journaled therein a longitudinal rod 39 with a disk 40 fixed to each rod in radial alinement with a clamp lever 35, a link rod 41 being eccentrically

connected as at 42 to the disk 40 and extending through a perforation in the clamp arm 35 with a head 41' formed upon the outer end thereof while a coil spring 43 surrounds the link rod between the rod head 41

and the outer face of the clamp lever, the spring normally forcing the clamp lever inwardly of the link rod 41 to be engaged by the stop pin 44 on the link rod inwardly

90 of the clamping lever, this construction being clearly shown in Fig. 2. The ends of the rods 39 project beyond the end wall 4 of the drum as at 39' and carry lateral arms 45 connected at their outer ends to rods 46

that carry cam rollers 47. A cam of the positive operating type, and as clearly shown in Figs. 1 and 5 is secured to the end standard 1, the cam being U-shaped in cross section embodying an outer wall 48 and an inner wall 49 with the cam rollers 47 traveling between the inner and outer walls and adapted for shifting movement to partially rotate the rods 39 by contact with the cam surfaces 48' and 49' of the cam walls. As

100 shown in Fig. 5 the cam is secured to the end standard 1 by bolts 50 extending through concentric slots 51 formed in the inner wall of the cam so that the cam may be shifted to change the position of the cam surfaces 48' and 49' relative to the vertical

105 axis of the standards for changing the position of the opening and closing movements of the clamping levers during rotation thereof as will be plainly obvious. This feature

110 of the invention is clearly disclosed in Figs. 2 and 5, the cam being shifted from one position to another to change the relative rotative positions of the clamp levers for their opening and closing movements. During

115 rotation of the drum 6 on the stub shaft 7 and the fluid supply pipe 9 the shafts 39 carried by the drum present the cam rollers 47 for operation by the cam surfaces 48' and 49' of the cam, the cam shifting the lateral arms 45 to partially rotate the shafts 39 and

120

125

130

the disks 40 carried thereby to move the link rods 41 inwardly and outwardly of the channels 38 with a like movement of the clamp levers 35, moving the rail clamping ends 37 of the levers toward and away from the pockets 21 and resiliently maintaining the clamp levers in closed position by the cushion spring 43 upon the link rods 41, the clamp levers being moved to their open position by gravitation and also influenced by pins 44 upon the link rods and cam and link rod connections shown in Fig. 2^a. The machine being continuous in operation, the rails A delivered from the rolling mill are received on the hot bed 52 formed of spaced bars in the usual manner with the outer ends of the bars of the hot bed 52 terminating adjacent the drum 6, the clamp levers 35 carried by the drum passing upwardly through the spaces between the bars of the hot bed in a manner as will be evident from an inspection of Fig. 2. The rails A are moved over the hot bed 52 and positioned for engagement by the clamp levers 35 by mechanism shown in Fig. 2, the same including a rack bar 53 slidably associated with the hot bed and carrying weighted bell cranks 54 for engaging the rails to shift the same along the hot bed as illustrated. Stop lugs 54' are carried by the rack bar to limit the swinging movement in one direction of the bell cranks and are counterbalanced to permit the ends of the bell cranks projecting above the hot bed to escape the rails when the rack bar is retracted. To operate the rack bar a segment rack 55 is pivotally mounted on a standard 56 and has the frame 57 thereof pivotally connected to one end of a pitman rod 58, the other end of which is eccentrically connected as at 59 to the gear 19, the pitman rod 58 being provided with the turn buckle connection 58' to vary the length of reciprocating movement of the rack bar 53.

In the operation of the device as shown in Figs. 1 and 2 the rails A heated above the critical temperature are successively delivered to the hot bed 52 and are transported over the hot bed upon rotation of the drum 6 through the medium of the gear 19 and the rack bar and segment rack mechanism, the bell cranks 54 engaging the rails to move the same forward in a step by step movement and retracting for engagement with other rails. The rails A are delivered to the forward end of the hot bed and as the clamp levers 35 move upwardly between the bars of the hot bed the ends 37 of the clamp levers engage the base flanges and webs of the rails as shown in Fig. 2 to remove the same from the hot bed. Upon rotation of the drum 6 the cam operates the rods 39 and through the medium of the disks 40 and link rods 41 the levers 35 are moved to position the heads of the rails between

the flanges 31 of the tensioned plates 30, the heads of the rails forcing the plates 30 apart while the springs 34 maintain closest contact of the plate flanges with the heads of the rails, and substantially seal the outer sides 70 of the pockets 21. During this movement the rail head engages the outer stems 28 of the valves 26 to unseat the valves against the tension of the springs 29, thereby permitting the hardening fluid within the drum 75 passing through the valve openings 23 and ports 22' in the pocket partitions 22 for contact with the heads of the rails. The hardening medium confined within the pockets 21 escapes therefrom through lateral vents 80 shown in Figs. 2, 3 and 6 while the base flanges and webs of the rails are protected from contact with the hardening medium. The rotation of the drum 6 is timed to permit the complete hardening of the rail 85 heads and a natural tempering of the rail webs and base flanges while the rails are supported on the drum. Continued movement of the drum 6 will cause an operation of the shafts 39 by the cam 48 and mechanism associating the cam and shaft 39 to permit rotation of the disks 40 and outward movement of the clamp levers 35 by the pins 44 on the link rods 41 and further influenced by the weight of the rails, the rails being discharged onto the chute 61 with the temperature thereof below the critical temperature so that any heat remaining in the rails will not be sufficient to again raise 95 the temperature of the rails above the critical temperature and affect the completed hardening process. By the provision of the tensioned plates 30 having the flanges 31 thereof engaging the sides of the rail heads the outer ends of the pockets 21 are substantially sealed at all times so that expansion or contraction of the rail heads will not displace the tensioned plates from engagement therewith. To compensate for hot beds of 100 different heights the cam may be rotatably adjusted to vary the points of opening and closing movements of the clamp levers relative to the hot bed, the cam being rotatable through the pin and slot connection 50 and 105 51 with its support. When the rails are discharged from the drum the valves 26 are moved to their seats 23 by the springs 29, thus sealing the adjacent pocket 21 from communication with the interior of the drum, the valves being automatic in their 110 operation.

In the form of the invention shown in Fig. 3 the valve structure is identical with the invention as disclosed in Figs. 1 and 2, the plates 30' carrying inwardly directed spaced flanges 31' for engagement with the rail head as illustrated, the plates 30' having pin and slot connections with the opposite walls of the pocket 21. In lieu of the tensioned pins 33' rack bars 33' are carried 115 120 125 130

by the flanges 31' and extend through openings in the side walls of the pockets for engagement with pinions 62 mounted on longitudinal rods 62' as shown in Fig. 6 that are 5 suitably operated to move the rack bars and flanges carrying the same inwardly for frictional contact with the sides of the rail heads. Also, if desired, one of the plate members 30' may be primarily fixedly adjusted to one wall of the pocket and the cooperating plate adjusted by the rack and pinion for engagement with the rail head. In this form of the invention the angle of the clamp lever 35' is changed with respect 10 to the lever 35 shown in Fig. 2 with the free end thereof connected to a shiftable rack block 68 operated by a pinion 64 to shift the clamping lever relative to the pocket 21, thus to accommodate a standard construction of 15 clamping arm to rails of different sizes, the opening and closing mechanism for the clamping arm 35' being identical with the operating mechanism for the clamping arms 35 as shown in Fig. 2.

20 Another form of the invention is shown in Fig. 4 wherein tubular clamping jaws 65 are pivotally supported on opposite walls of the pocket 21 with the opposite sides of the head of the rail positioned between the jaws, and when the jaws are in the position shown 25 in Fig. 4 the inner jaw faces are slightly spaced from the top of the rail head to permit the flow of hardening medium in the pocket onto the rail head and into the tubular jaws to escape therefrom through the 30 vent openings 66. In this form of the invention the clamp lever 35 is pivoted to the lug 36 to one side of the channel 38 while the rail engaging end 37 of the clamp lever 35 is provided with adjustable slides 67 for engaging the opposite sides of the base flanges of the rail to more securely anchor the same in position. When the drum 6 is 40 rotated and being provided with the tubular clamping jaws 65 shown in Fig. 4 the jaws are moved outwardly on their hinge connections with the opposite walls of the pockets by the rail heads engaging the outer faces 45 of the jaws and will remain so positioned until the clamp 35 receives a rail to be tempered and moves the same inwardly for engagement with the inner face of the jaws which will fall by gravity to the position 50 shown in Fig. 4 when the clamp levers are moved home.

55 A still further form of the invention is shown in Fig. 7, wherein the pockets for receiving the heads of the rails are formed of spaced longitudinal ribs 46' with transverse webs 47' supporting the head of the rail, perforations being provided in the bottom walls of the pocket to permit the flow of hardening medium in contact with the rail heads when the valves are unseated in

65 a manner hereinbefore described, the remaining elements of this form of the invention being of like construction and operating in a similar manner.

70 The present apparatus for hardening rails provides for the continuous movement of the rail when delivered on the hot bed from the rolling machine and during the hardening process, the rails successively delivered to the hot bed being successively received 75 on the rotating drum and hardened during the partial rotation of the drum, the rails remaining on the drum during the hardening process until the temperature thereof falls below the critical temperature so that 80 the heat remaining in the rails will not be sufficient for redistribution through the rail structure to raise the temperature to a point above the critical temperature, and while there are herein shown and described the 85 preferred forms of the invention, it is to be understood that various changes in details of construction are contemplated without departing from the spirit and scope of the invention as claimed. It is further intended 90 not to limit this application to the character of hardening medium employed, or the manner of supplying the same to the drum, as water or oil may be used with equal efficiency, and delivered to the drum in any 95 manner desired.

95 What is claimed as new is:—

1. Apparatus for hardening steel rails including rail supporting means supplied with a hardening medium, means for delivering rails to the supporting means, and means 100 for automatically releasing the rails from the supporting means after hardening thereof.

2. Apparatus for hardening carbon steel, comprising in combination, means for successively feeding carbon steel articles to a point of supply, and means for successively transferring said steel articles to a point of discharge, said transferring means operating to cool the steel articles moderately rapidly 110 by means of an elastic fluid contained therein, and tensioned members gripping the steel articles during the hardening operation.

3. Apparatus for hardening steel rails, including rail supporting means supplied with a hardening medium, and automatically operating means carried exteriorly of the rail supporting means cooperating with the rails to be hardened for directing the hardening medium within the supporting means onto 115 the rail heads and protecting the rail webs and flanges.

4. Apparatus for hardening steel rails, including rail supporting means supplied with a hardening medium, and adjustable means 120 positioned exteriorly of the rail supporting means cooperating with the rails to be hardened for directing the hardening medium 125

within the supporting means onto the rail heads and protecting the rail webs and flanges.

5. Apparatus for hardening steel rails, including rail supporting means supplied with a hardening medium, and shiftable means positioned outwardly of the rail supporting means cooperating with the rails to be hardened for directing the hardening medium within the supporting means onto the rail heads and protecting the rail webs and flanges.

6. Apparatus for hardening steel rails, including rail supporting means supplied with a hardening medium, and resiliently mounted means carried by the rail supporting means cooperating with the rails to be hardened for directing the hardening medium onto the rail heads and protecting the rail webs and flanges.

7. Apparatus for hardening steel rails, including rail supporting means supplied with a hardening medium, and laterally adjustable means positioned exteriorly of the rail supporting means cooperating with the rails to be hardened for directing the hardening medium within the supporting means onto the rail heads and protecting the rail webs and flanges.

8. Apparatus for hardening steel rails, including rail supporting means supplied with a hardening medium, and laterally shiftable means positioned exteriorly of the rail supporting means cooperating with the rails to be hardened for directing the hardening medium within the supporting means onto the rail heads and protecting the rail webs and flanges.

9. Apparatus for hardening steel rails, including rail supporting means supplied with a hardening medium, and laterally movable resiliently mounted means carried by the rail supporting means cooperating with the rails to be hardened for directing the hardening medium onto the rail heads and protecting the rail webs and flanges.

10. Apparatus for hardening steel rails, including a rotatable rail supporting drum supplied with a hardening medium, and means carried by the drum cooperating with the rails to be hardened for directing the hardening medium within the supporting drum onto the rail heads and protecting the rail webs and flanges.

11. Apparatus for hardening steel rails, including a rotatable rail supporting drum supplied with a hardening medium, and adjustable means carried by the drum cooperating with the rails to be hardened for directing the hardening medium within the supporting drum onto the rail heads and protecting the rail webs and flanges.

12. Apparatus for hardening steel rails, including a rotatable rail supporting drum supplied with a hardening medium, and

shiftable means carried by the drum cooperating with the rails to be hardened for directing the hardening medium within the supporting drum onto the rail heads and protecting the rail webs and flanges.

13. Apparatus for hardening steel rails, including a rotatable rail supporting drum supplied with a hardening medium, and resiliently mounted means carried by the drum cooperating with the rails to be hardened for directing the hardening medium onto the rail heads and protecting the rail webs and flanges.

14. Apparatus for hardening steel rails, including a rotatable rail supporting drum supplied with a hardening medium, and laterally adjustable means carried by the drum cooperating with the rails to be hardened for directing the hardening medium within the supporting drum onto the rail heads and protecting the rail webs and flanges.

15. Apparatus for hardening steel rails, including a rotatable rail supporting drum supplied with a hardening medium, and laterally shiftable means carried by the drum cooperating with the rails to be hardened for directing the hardening medium within the supporting drum onto the rail heads and protecting the rail webs and flanges.

16. Apparatus for hardening steel rails, including a rotatable rail supporting drum supplied with a hardening medium, and laterally movable resiliently mounted means carried by the drum cooperating with the rails to be hardened for directing the hardening medium onto the rail heads and protecting the rail webs and flanges.

17. Apparatus for hardening steel rails, including a rotatable rail supporting drum supplied with a hardening medium, peripherally spaced longitudinally extending pockets formed in said drum, tensioned valves for controlling the flow of hardening medium from the drum to the pockets, rail engaging clamps carried by the drum for supporting a rail with the rail head extending into the adjacent pocket, and means arranged at opposite sides of the pockets engaging the rail head to close the outer ends of the pockets.

18. Apparatus for hardening steel rails, including a rotatable rail supporting drum supplied with a hardening medium, peripherally spaced longitudinally extending pockets formed in said drum, tensioned valves for controlling the flow of hardening medium from the drum to the pockets, rail engaging clamps carried by the drum for supporting a rail with the rail head extending into the adjacent pocket, and means arranged at opposite sides of the pockets engaging the rail head, to close the outer ends of the pockets adjacent the rail heads, the side walls of the pockets having lateral vent openings therein.

19. Apparatus for hardening steel rails including a rotatable rail supporting drum supplied with a hardening medium, peripherally spaced longitudinally extending pockets formed in said drum, tensioned valves for controlling the flow of hardening medium from the drum to the pockets, rail engaging clamps carried by the drum for supporting a rail with the rail head extending into the adjacent pocket, and tensioned flanged plates arranged at opposite sides of the pockets engaging the rail heads to close the outer ends of the pockets adjacent the rail heads.
20. Apparatus for hardening steel rails including a rotatable rail supporting drum supplied with a hardening medium, peripherally spaced longitudinally extending pockets formed in said drum, tensioned valves for controlling the flow of hardening medium from the drum to the pockets, rail engaging clamps carried by the drum for supporting a rail with the rail head extending into the adjacent pocket, and tensioned flange plates arranged at opposite sides of the pockets, the side walls of the pockets having lateral vent openings therein.
21. Apparatus for hardening steel rails, including a rotatable rail supporting drum supplied with a hardening medium, peripherally spaced longitudinally extending pockets formed in said drum, tensioned valves for controlling the flow of hardening medium from the drum to the pockets, rail engaging clamps carried by the drum for supporting a rail with the rail head extending into the adjacent pocket, and laterally shiftable flanged plates arranged at opposite sides of the pockets engaging the rail heads to close the outer ends of the pockets adjacent the rail heads.
22. Apparatus for hardening steel rails, including a rotatable rail supporting drum supplied with a hardening medium, rail receiving pockets formed in the periphery of the drum, rail engaging clamps for supporting rails in the pockets, rotatable shafts extending longitudinally of the drum, operative connections between the clamps and said shafts, and a rotarily adjustable cam associated with said shaft to vary the point of operation of the clamps relative to the rotative positions of the drum.
23. Apparatus for hardening steel rails, including a rotatable drum supplied with a hardening medium, rail receiving pockets formed in the periphery of said drum, rail engaging clamps carried by the drum for positioning rail heads in the pockets, and pivotally mounted tubular clamping jaws for the rail heads arranged in said pockets for closing the outer ends of the pockets adjacent the rail heads and to protect the rail webs and flanges from the hardening medium.
24. Apparatus for hardening steel rails, including a rotatable drum supplied with a hardening medium, rail receiving pockets formed in the periphery of said drum, rail engaging clamps carried by the drum for 70 positioning rail heads in the pockets, and pivotally mounted tubular clamping jaws for the rail heads arranged in said pockets for closing the outer ends of the pockets adjacent the rail heads and to protect the rail webs and flanges from the hardening medium, said tubular jaws having the inner jaw faces spaced from the rail heads when the rails are being hardened and having vent openings in the outer sides thereof directing 80 the escape of the hardening medium laterally of the rail webs and flanges.
25. In combination with the hot bed of a steel rail rolling mill, apparatus for hardening steel rails, including a rotatable 85 drum supplied with a hardening medium, and means carried by the drum moving in proximity of said hot bed for transferring rails from the hot bed to the drum to be hardened.
26. In combination with the hot bed of a steel rail rolling mill, apparatus for hardening steel rails, including a rotatable drum supplied with a hardening medium, means carried by the drum moving in 90 proximity of said hot bed for transferring rails from the hot bed to the drum to be hardened, and means associated with the hot bed for moving rails thereover for reception on said drum.
27. In combination with the hot bed of a steel rail rolling mill, apparatus for hardening steel rails, including a rotatable drum supplied with a hardening medium, means carried by the drum moving in 95 proximity of said hot bed for transferring rails from the hot bed to the drum to be hardened, means associated with the hot bed for moving rails thereon for reception on said drum, and operative connections between the rail moving means and rotatable drum.
28. In combination with the hot bed of a steel rail rolling mill, apparatus for hardening steel rails, including a rotatable 110 drum supplied with a hardening medium, means carried by the drum moving in proximity of said hot bed for transferring rails from the hot bed to the drum to be hardened, a rack bar carrying pivoted dogs 115 slidably associated with the hot bed, a segment rack in mesh with said rack bar, and operative connections between the segment rack and rotatable drum.
29. Apparatus for hardening the heads of steel track rails after rolling, comprising in combination, continuously movable means supplied with a hardening medium for hardening the rail heads, means for successively feeding the track rails in a step by 125 130

step movement to the first named means, said first named means successively transferring the track rails to a point of discharge and operating to cool the heads of the track rails by directing the hardening medium contained therein only against the heads of the rails.

30. The method of hardening steel rails after rolling consisting in feeding the rails to a point of supply with a step by step movement, continuously moving and hardening said rails at the point of supply and then successively delivering the rails to a point of discharge.

31. The method of hardening steel rails after rolling consisting in successively moving the rails to a hardening device, then con-

tinuously moving and hardening the rails on said device and finally successively discharging the rails therefrom.

20

32. The method of hardening steel rails after rolling, consisting in moving the rails in a step by step movement to a hardening device, hardening said rails and simultaneously moving the same to a point of discharge, and finally discharging the rails from the hardening device.

In testimony whereof I affix my signature in presence of two witnesses.

CHARLES A. EWING.

Witnesses:

WILLIAM F. HOUSMAN,
LAWRENCE A. NESSLE.
